UNITED STATES PATENT OFFICE.

EUGENE F. OSBORNE, OF CHICAGO, ILLINOIS, ASSIGNOR TO OSBORNE STEAM ENGINEERING COMPANY, OF CHICAGO, ILLINOIS, A CORPORATION OF ILLINOIS.

APPARATUS FOR SUPERHEATING STEAM.

No. 889,147.

Specification of Letters Patent.

Patented May 26, 1908.

Original application filed April 8, 1901, Serial No. 54,920. Divided and this application filed May 23, 1904.
Serial No. 209,363.

To all whom it may concern:

Be it known that I, EUGENE F. OSBORNE, a citizen of the United States, and a resident of Chicago, in the county of Cook and State 5 of Illinois, have invented certain new and useful Improvements in Apparatus for Superheating Steam; and I do hereby declare that the following is a full, clear, and exact description thereof, reference being had to 10 the accompanying drawings, and to the letters of reference marked thereon, which form a part of this specification.

This invention relates to improvements in apparatus for superheating steam for use in 15 steam engines and like uses and located between the steam generator and the engine or other point of use whereby a greater expansion of the steam may be secured and more power generated therefrom.

20 Among the objects of the invention is to provide an improved apparatus whereby steam may be safely superheated to a suitably high temperature for economic work and practice without danger to the superheating apparatus, and a further object of 25 the invention is to produce an apparatus by which the temperature of the steam may be maintained practically constant notwithstanding variations of the demand for the 30 steam.

The superheater herein disclosed is of a class which may be termed a liquid superheater, wherein the heat to superheat the steam is transmitted to the steam through 35 the medium of a liquid, (preferably having a higher boiling point and lower vaporizing point than water) as distinguished from what may be termed dry superheaters wherein the steam is superheated by the direct action of 40 flames playing about the pipes through which the steam passes. In the first class of superheater, or that to which this invention belongs, there is interposed between the fire that superheats the steam and the steam that 45 is being superheated, two walls and a body of the superheating agent referred to. The superheating agent may be heated by a source of heat external to and independent of that which generates the steam and may be 50 therefore termed an independently fired superheater. Such a superheater possesses greater practical efficiency than a dry superheater and is more durable and safe because of the fact that in the construction of such

dry superheaters, if the apparatus be so located relatively to the boiler furnace as to be efficient, it becomes unsafe because of the high temperature to which the superheater is exposed, while on the other hand if the apparatus be so located as to be relatively safe it becomes inefficient. In the present invention the steam may be heated to as high a temperature as may be practically desirable while at all times the apparatus is highly efficient and durable and entirely safe.

I have shown in the drawings one form of apparatus which may be conveniently employed for carrying out my invention, said drawings showing diagrammatically a steam 70 superheating device and a steam generator, and illustrating the manner in which it is connected with the generator.

As shown in said drawings, A designates a steam generator which is designed to supply 75 steam to operate an engine (not shown) in the usual manner.

B designates as a whole, a heat transmitter, consisting of a casing which is closed at its ends by end walls b b¹. Said casing is provided 80 interiorly with two diaphragms or heads B¹ B² which divide the casing into an intermediate chamber B³ and two end chambers B⁴ B⁵. Contained within said intermediate chamber is a plurality of parallel tubes 85 B⁶ which extend between the diaphragms or heads B¹ B² and open therethrough in a manner to afford communication between said chambers B⁴ B⁵.

C designates a pipe leading from the boiler 90 A and discharging into and communicating with the lower end of the intermediate chamber B³.

D designates a pipe which leads from the upper end of said intermediate chamber B³ 95 and is adapted for connection with the steam chest of an engine (not shown).

E designates a pipe which communicates with the lower chamber B⁴ of the heat transmitter and terminates at its lower end in a 100 coil E¹, and E² designates a pipe which extends from the opposite end of said coil to the upper chamber B⁵ of the heat transmitter. The coil E¹ is subjected to heat from a suitable burner and is shown as inclosed within a 105 chamber F. The burner for heating the contents of the coil consists, as herein shown, of a gas burner G located in the bottom of the

chamber F and supplied with fuel through the medium of a supply pipe G¹.

H designates a thermostat which is located within a fitting D¹ forming a part of the steam eduction pipe D. Said thermostat is operatively connected with the upper end of a rod I, the lower end of which rod is connected with a valve G² which is located within the fuel supply pipe G¹.

G³ designates a pipe leading from the supply pipe G¹ at a point outside the valve G² to a burner jet g located within or adjacent to the annular burner G. The burner g serves as a pilot burner for relighting the main burner in case the supply of gas thereto should be entirely cut off temporarily by the action of the thermostat.

The pipe E, coil E¹ and pipe E², the end chambers B⁴ B⁵ and the tubes B⁶ constitute a heat conducting circuit through which is circulated a liquid superheating agent, while the pipe C, chamber B³ and pipe D constitute a passage for the steam by means of which the same is brought into heat transmitting relation with the superheating agent circulated in the heat conducting circuit. Said superheating agent receives heat from the burner G and is caused to circulate continuously through the heat transmitting circuit so long as heat is applied thereto. The steam is continuously passed over the tubes B⁶ of the heating conducting circuit, and a portion of the heat of the superheating agent is given off to the steam with the result of raising the temperature of the steam or superheating the same. The liquid used as a superheating agent is preferably one which has a boiling higher heating temperature than that of the water from which the steam is generated, so that a higher temperature may be maintained in the superheating circuit than in the steam generator or boiler, with little or no pressure in said circuit. In this manner a suitably high temperature may be maintained to highly superheat the steam without endangering the superheating apparatus. The liquid employed as a heat conducting medium may be linseed oil, brine, a metal having a low fusing point and a high boiling point, or any other suitable fluid. It will be observed that the steam passes through the heat transmitter in a direction opposite to the direction of flow of the superheating agent, whereby the hottest part of the superheating agent within the transmitter is brought into heat transmitting relation to the hottest steam and the gradually cooling superheating agent is brought into like relation to the incoming or cooler steam. This arrangement is preferred by reason of its greater efficiency and is equally preferable with any kind of liquid superheating agent.

K designates a safety valve which is in communication with the upper chamber B⁵ of the heat transmitting casing and which

provides against injury to the casing from pressure of vapor or gas rising from the heating conducting medium.

As before stated, the thermostat I is located within the discharge pipe D of the heat transmitting chamber or that leading to the point of use or consumption of the superheated steam so as to be subjected to the full influence of the superheated steam after it leaves said heat transmitting chamber. The thermostat is adjusted in a manner to be actuated at a selected temperature, or at a temperature at which it is desired to maintain the steam in the pipe D, so that it will be operated to actuate the valve at a variation from such selected or given temperature either above or below the same. In other words, when the temperature of the steam exceeds that which has been predetermined, the thermostat operates to close the valve G² to decrease or cut-off the supply of fuel to the coil E¹ while, on the other hand, when said temperature is reduced below that of such predetermined point, the thermostat operates to open the valve and permit an increased supply of fuel to said burner with a corresponding increase in temperature of the superheating agent.

While I have herein shown the heat conducting circuit as supplied with heat from a vapor or gas burner, it will be obvious that the source of heat to the circulating medium may be the furnace which supplies the boiler A with heat. In this case, a flue may be directed from said furnace to the casing, such as the casing F and said flue provided with a damper which may be connected with the thermostat and operated in a manner similar to that in which the valve G² is operated. Moreover, in case the regulation of the heat applied to the superheating agent is not required, such heat may be derived from the furnace of the generator itself and without the intervention of dampers and regulating apparatus.

One of the important advantages arising from the use of the apparatus described is that the source of heat is entirely outside of and independently controllable with respect to the heat applied to the steam generator, so that the conditions which govern the heating of the steam generator will have no effect on the heat which is applied to the superheating agent. An advantage of the regulation of the heat applied to the heat conducting circuit is that the temperature of the steam may be maintained practically constant, and the use of the fuel to heat the superheating agent is economical.

The process herein disclosed is claimed in my co-pending application for U. S. Letters Patent, No. 54,920, filed April 8th, 1901, of which this application is a division.

I claim as my invention:

1. An apparatus for superheating steam

comprising, in combination with a steam generator, a superheater arranged between the generator and the point of use of the steam through which the steam passes to its point of use, said superheater embracing a passage or passages in which circulates a liquid, through which liquid and the walls of the passage or passages the heat to superheat the steam is transmitted, a source of heat for heating said transmitting liquid and means for varying the intensity of the heat applied to said transmitting liquid.

2. An independently fired steam superheating apparatus comprising, in combination with a steam generator, a superheater arranged between the generator and point of use of the steam through which the steam passes to its point of use, said superheater embracing a passage or passages in which circulates a liquid, through which liquid and the walls of the passage or passages the heat to superheat the steam is transmitted, a source of heat independent of that which heats the steam in the generator for heating the said transmitting liquid, and means controlled by the temperature of the steam which passes from the superheating apparatus for varying the intensity of the heat applied from said source to said transmitting liquid.

3. An independently fired steam superheating apparatus comprising, in combination with a steam generator, a superheater arranged between the generator and point of use of the steam through which the steam passes to its point of use, said superheater embracing a passage or passages in which circulates a liquid, through which liquid and the walls of the passage or passages the heat to superheat the steam is transmitted, a source of heat independent of that which heats the steam in the generator for heating the said transmitting liquid, and means controlled by the temperature of the steam which passes from the superheating apparatus for varying the intensity of the heat applied from said source to said transmitting liquid.

In testimony, that I claim the foregoing as my invention I affix my signature in presence of two witnesses, this 12th day of May A. D. 1904.

EUGENE F. OSBORNE.
